UNITED STATES PATENT OFFICE.

ELMER E. KERNS, OF BRADFORD, PENNSYLVANIA.

DESIGN FOR A BADGE.

SPECIFICATION forming part of Design No. 29,116, dated August 2, 1898.

Application filed June 13, 1898. Serial No. 683,368. Term of patent 31 years.

To all whom it may concern:

Be it known that I, ELMER E. KERNS, a citizen of the United States, residing at Bradford, in the county of McKean and State of Pennsylvania, have invented a new and useful Design for Badges, of which the following is a specification.

My invention relates to designs for badges, as represented in the accompanying drawings, 10 of which—

Figure 1 is a front view, and Fig. 2 is a vertical sectional view thereof.

The design consists of a base in outline, similar to a keystone, the surrounding edge 15 of the base being provided with a plurality of stars. Situated at the center of the base,

which forms the background, and surrounded by the stars is a Cuban flag. The flag is placed in a background of a different color from the base, as illustrated.

Having thus described my design, what I claim, and desire to secure by Letters Patent, is—

The design for a badge substantially as shown and described.

In testimony whereof I have hereunto set my hand in the presence of two subscribing witnesses.

ELMER E. KERNS.

Witnesses:

HERMAN H. NORTH,
JOHN P. CALVERT.
